[57] CLAIM

The ornamental design for a tail piece for a banjo, as
shown and described.

DESCRIPTION

FIG. 1 is a top plan view of a tail piece for a banjo
showing my new design;

FIG. 2 is a front elevational view thereof;

FIG. 3 is a right side elevational view, the left side being
a mirror image thereof;

FIG. 4 is a rear elevational view thereof; and

FIG. 5 is a bottom plan view thereof.

FIG. 1

FIG. 2

FIG. 3

FIG. 5

FIG. 4
